ASSEMBLING DEVICE

Edwin S. Timmons, Chicago, Ill.

Application July 30, 1932. Serial No. 626,856

3 Claims. (Cl. 29—84)

This invention relates generally to a device for assembling together the vanes of a vehicle light director which is of the same general character as disclosed in my co-pending application, Serial No. 626,855, filed of even date. In the construction of a vane unit, as will hereinafter be described, it is imperative that the vanes be spaced in parallelism while being assembled in a frame. Due to the fact that the vanes are made of very thin metal, it is a particular problem to handle them without bending or distorting them so that the light rays which pass therebetween will not be interrupted.

The present device is adapted to receive a plurality of vanes in spaced relation and to hold the same while being attached to a supporting frame, whereupon the assembled unit is moved out of the assembling device and is ready to be installed in an automobile headlight.

As an exemplification of my invention, reference is made to the accompanying drawing, in which—

Figure 1 is a view in side elevation of the assembling device with a supporting frame placed thereon;

Fig. 2 is a plan view of the same;

Fig. 3 is an enlarged fragmentary view in section taken on line 3 of Fig. 2;

Fig. 4 is a fragmentary view in section taken on line 4 of Fig. 2; and

Fig. 5 is a partial view of the vane unit completely assembled.

Referring to the drawing, wherein is shown a base upon which is rigidly mounted a plurality of spacers B, and a frame C which is movable toward and away from the base for lifting the assembled vane unit D from the device after being assembled.

The base is provided with a longitudinal opening 10 in which is rotatably mounted a shaft 11, having a central reduced portion 12 fitted in a bearing 13 which prevents longitudinal movement of the shaft. On one end of the shaft is a right-hand thread, and on the opposite end is a left-hand thread, each end being in threaded engagement with a block 14 (one only being shown). The shaft may have mounted on one end a crank 15 by which the shaft is rotated to move the blocks 14 toward or from the base.

The blocks are prevented from rotating with the shaft by plates 16 extending outwardly from the base and adjacent the block. Extending outwardly from the ends of each block are trunnions 17, on which are mounted links 18, the opposite ends of which are pivotally connected

at 19 to the frame C, the purpose of which will later be explained.

Secured to the upper side of the base are blocks 20 and 21 between which are fitted spacers 22 and shims 23, the spacers and shims being clamped by screws 24 against the blocks 20. By referring to Fig. 3 it will be seen that the spacers and shims are arranged alternately side by side, the shims being narrow so as to leave thereabove spaces 25, into which are received the vanes B. Preferably, the shims are one or two thousandths of an inch thicker than the vanes to provide suitable space for the free insertion thereof.

Each spacer may be shaped rectangular or square and of a size suitable to conditions, as, for example, in Fig. 2 are shown spacers of four different lengths so as to receive thereabout a circular frame D. Each spacer is pointed or beveled along its outermost edge, as shown at 26 (Fig. 3) to facilitate the insertion of the vanes. The spacers are provided with suitable slots 27 in which is slidably received the frame C, which comprises end bars 28 rigidly connected together by spaced rods 29 which lie in the slots 27. Each of the end bars 28 are provided with openings 30 through which extend pins 31 which are secured in the base, the pins acting as guides for the frame C.

A vane unit may be assembled in the following manner: With the frame C lowered in the slots 27 to a desired point, as shown in Figs. 1, 3 and 4, vanes v are placed in the spaces 25 and moved downwardly so as to contact the upper edges of the rods 29. The frame w is then placed upon the rods 29 surrounding the vanes, after which rods x are inserted through openings in the frame w and vanes v, and secured thereto in a manner described in my co-pending application above referred to. Plates y, which are inserted in the device along with the vanes, may then be connected to the frame w by openings z, as shown, after which the crank 15 may be rotated to turn the shaft 11, thereby moving the blocks 14 toward the base A, which movement causes the frame C to be raised by the links 18 to the position shown in dotted lines in Fig. 1, when the vane assembly D is entirely disassembled from the device.

The present device is advantageous in that the vanes, which are very thin and easily bent, may be properly spaced apart with little difficulty. They are protected by the spacers against being bent, and are firmly held while being secured to the rods x which support them.

I claim:

1. In a device for assembling parallel vanes upon a support including a plurality of alternately arranged spacers in the form of sheets and shims secured together, the shims being of less width than the spacers and located adjacent one edge thereof so as to provide spaces for the insertion of vanes adjacent the opposite edges of the spacers, the vanes while in such position being adapted to be secured to the support, and means for removing the vanes simultaneously from between the spacers. 80
2. In a device for assembling parallel vanes upon a support including a base, spaced blocks formed in the base and extending upwardly therefrom, a plurality of alternately arranged spacers in the form of sheets and shims rigidly secured between the blocks, the shims being of less width than the spacers and located adjacent one edge thereof so as to provide spaces for the insertion of vanes adjacent the opposite edges of the spacers and in the same plane with the shims, the vanes being held in this position while secured to the support, and a frame located normally beneath the vanes and lying within the slots in the spacers and movable relative to the base whereby the vanes are removed from between the spacers after assembling. 85
3. In a device for assembling parallel vanes upon a support including a base, spaced blocks formed in the base and extending upwardly therefrom, a plurality of alternately arranged spacers in the form of sheets and shims rigidly secured between the blocks, there being transversely aligned slots in the spacers, the shims being of less width than the spacers and located adjacent one edge thereof so as to provide spaces for the insertion of vanes adjacent the opposite edges of the spacers and in the same plane with the shims, the vanes being held in this position while secured to the support, and a frame located normally beneath the vanes and lying within the slots in the spacers and movable relative to the base whereby the vanes are removed from between the spacers after assembling. 90

cured to the support, and a frame located normally beneath the vanes and movable relative to the base whereby the vanes are removed from between the spacers after assembling.

3. In a device for assembling parallel vanes upon a support including a base, spaced blocks formed in the base and extending upwardly therefrom, a plurality of alternately arranged spacers in the form of sheets and shims rigidly secured between the blocks, there being transversely aligned slots in the spacers, the shims being of less width than the spacers and located adjacent one edge thereof so as to provide spaces for the insertion of vanes adjacent the opposite edges of the spacers and in the same plane with the shims, the vanes being held in this position while secured to the support, and a frame located normally beneath the vanes and lying within the slots in the spacers and movable relative to the base whereby the vanes are removed from between the spacers after assembling. 95
